R. E. Hamilton

UNITED STATES PATENT OFFICE.

WILLIAM P. CAMPBELL, OF KANSAS CITY, MISSOURI, ASSIGNOR OF FORTY-NINE ONE-HUNDREDTHS TO HARRY W. TULLY AND JOHN H. LANE, AND OF FIFTY-ONE ONE-HUNDREDTHS TO JOHN H. LANE, ALL OF KANSAS CITY, MISSOURI.

STABILIZING DEVICE.

Application filed January 29, 1923. Serial No. 615,594.

To all whom it may concern:

Be it known that I, WILLIAM P. CAMPBELL, a citizen of the United States, residing at Kansas City, in the county of Jackson and State of Missouri, have invented a certain new and useful Improvement in Stabilizing Devices, of which the following is a specification.

My invention relates to improvements in 10 stabilizing devices for automobile steering mechanisms.

One of the objects of my invention is to provide a device which will yieldingly hold the spindle arms of an automobile from 15 wobbling or "shimmying", and which will also prevent rattling between the steering connecting rod and the spindle arm.

Still another object of my invention is to provide a device of the kind described, 20 which is simple, cheap to make, durable, not liable to get out of order, which will exert a substantially uniform resistance to the movement of the steering arms in either direction and hold them in the positions in 25 which they are placed, and which will not prevent the easy steering of the machine.

Still another object of my invention is to provide a device of the kind described 30 which can be readily applied to its operative position, and which will be readily held in such position without any securing devices other than its own form and resiliency.

The novel features of my invention are 35 hereinafter fully described and claimed.

In the accompanying drawing which illustrates the invention,

Fig. 1 is a top view, partly broken away, 40 showing the preferred embodiment of my invention in which the spring has a bearing against the axle, the steering rod and the steering arm.

Fig. 2 is a sectional view, enlarged, on the line 2—2 of Fig. 1.

Fig. 3 is a perspective view of the spring 45 shown in Figs. 1 and 2, the spring being shown enlarged.

Fig. 4 is an enlarged perspective view 50 of a modified form of the spring.

Fig. 5 is a view, similar to Fig. 2, showing 55 the spring shown in Fig. 4 applied to the steering connecting rod and the front axle.

Similar reference characters designate 55 similar parts in the different views.

1 designates the front axle of the double channel or I beam type, such as is commonly employed in certain machines which are on the market, and to which are pivoted in the usual manner the spindles 2 having each 60 a steering arm 3, the latter having pivoted to it the forked adjacent end of the usual steering connecting rod 4.

In both forms of my invention illustrated 65 in the drawing, a spring is located between the arms of the forked end of the adjacent end of the rod 4 and in the channel in the adjacent side of the axle 1 and embraces the upper and lower sides of the rod 4, the spring in both forms having a sliding bearing 70 on the axle, and in the form shown in Figs. 1 and 2 having a bearing against the connecting rod 4 and against the arm 3. In the form shown in Figs. 4 and 5, the spring bears on the axle and against the 75 connecting rod.

Referring to Figs. 1, 2 and 3, the spring shown comprises a spring wire doubled on itself and designated by 5, the U-shaped middle portion of the wire being disposed 80 between the arms of the adjacent forked end of the connecting rod 4 and bearing against the adjacent end of the steering arm 3 and exerting a constant pressure against the outer end of the connecting rod 85 4, the end portions of the wire 5 having a sliding frictional contact with and bearing against the adjacent side of the axle 1 and being held in place by the flanges of the channel on that side of the axle. The wire 5 has formed in it two coils 6 which 90 respectively embrace the upper and lower sides of the rod 4, thus securely fixing the spring against displacement. By means of this construction, the spring forms means 95 for affording a substantially uniform resistance against movement of the connecting rod 4 and spindle arms 3 in either direction. It also affords means for preventing rattling between the connecting rod and the 100 spindle arm. By having a sliding bearing against the axle, and thus exerting a uniform resistance to the movement of the steering rod and spindle arms in either direction, the spring does not interfere with 105 the easy steering of the machine, but pre-

vents the "shimmying" or wobbling of the front wheels. As is well known, such lateral vibration makes steering difficult and is a cause of discomfort and annoyance to the operator of the machine.

As is shown in Fig. 1, two springs 5 may be employed in connection respectively with the two steering arms 3 and the opposite ends of the connecting rod 4.

10 In the form of my invention, shown in Figs. 4 and 5, the spring comprises a wire 7 doubled on itself, similarly to the wire 5, the ends of the wire 7 being extended between the arms of the adjacent forked end of the rod 4, and being disposed laterally across said arms respectively, as shown in Fig. 5.

The middle bent U shaped portion of the wire 7 rests in the channel of the adjacent side of the axle 1. The wire 7 is provided 20 with two coils 8, similar to the coils 6, which respectively embrace the upper and lower sides of the rod 4.

25 In the form of my invention shown in Figs. 4 and 5, the spring 7 does not serve as an anti-rattler, but it provides a uniform resistance to the lateral movement in either direction of the steering rod 4, and, consequently, prevents "shimmying" or wobbling of the steering arms 3.

30 In applying the device, the spring is slipped between the arms of the forked end of the connecting rod 4, and is then sprung into the adjacent channel of the axle, the coils 6 and 8 being made to embrace the rod

35 4. The tension of the spring will cause it to stay in operative position. As the spindles are swung to and fro in steering, the spring, in sliding on the axle, will not interfere with the easy steering of the machine, and

40 will hold the spindle arms from wobbling due to the traveling of the front wheels along uneven ground.

I do not limit my invention to the structures shown and described, as modifications, within the scope of the appended claims, 45 may be made, without departing from the spirit of my invention.

What I claim is:—

1. In a device of the kind described, the combination with the front axle, the spindle 50 pivoted thereto and having a steering arm, and steering connecting rod having a forked end pivoted to the steering arm, of a spring between the arms of said forked end bearing against the rear end of the steering arm and against the front side of the steering rod and having a sliding bearing against the axle.

2. In a device of the kind described, the combination with the front axle, the spindle 60 pivoted thereto having a steering arm, and steering connecting rod pivoted to said steering arm, of a spring having portions disposed respectively above and below the connecting rod and having a bearing against 65 said spindle arm and having a sliding bearing against said axle by which the spindle arm is opposed by a substantially uniform pressure against movement in either direction.

3. In a device of the kind described, the combination with the front axle, the spindle pivoted thereto having a steering arm, and the steering connecting rod having a forked end pivoted to said arm, of a spring having 75 portions disposed respectively above and below the steering rod, and located between the arms of the forked end of the steering rod and bearing against the steering rod and the steering arm and having a sliding bearing against the axle.

In testimony whereof I have signed my name to this specification.

WILLIAM P. CAMPBELL.
